SHAKE-SPLITTING MACHINE

Axel E. Beckman, Oregon City, Oreg.

Application April 26, 1937, Serial No. 139,023

4 Claims. (Cl. 144—193)

This invention is directed to an apparatus for the manufacture of shakes and is constructed with a view to providing for the splitting from an appropriate block of a shake of the desired thickness at the butt end and of tapering formation from the butt end.

Heretofore, at least in the majority of instances, shakes have been formed by the use of cutting knives which are forced through the block, or saws which operate on the block, with the disadvantage that in the first instance the surface of the shake is naturally smooth and must be subsequently treated to get the desired roughness or grain, and in the second instance there is a considerable loss of material due to the cutting width of the saw.

The primary object of the present invention, therefore, is the provision of a wedge-shaped splitting element which may be forced into the block and split therefrom a shake of the desired thickness at the butt end, tapering from such butt end and having the natural rough grain finish by reason of its being split from the block rather than cut therefrom.

The invention is illustrated in the accompanying drawing, in which:

Figure 1 is a perspective view of the apparatus as a whole.

Figure 2 is a longitudinal sectional view of the machine shown in Figure 1.

Figure 3 is a similar view showing the splitting implement entering the block from the end opposite the operation indicated in Figure 2.

Figure 4 is an enlarged sectional view on the line 4—4 of Figure 2.

Figure 5 is a transverse section through the apparatus on the line 5—5 of Figure 2.

Figure 6 is a broken longitudinal section, partly in elevation, of the apparatus.

Figure 7 is a broken elevation showing the means for providing adjustable stroke lengths of the slide bar.

Figure 8 is a transverse section of the splitting tool.

The construction provides a frame including an upper box-like body 1 having side walls 2 and end walls 3, with the body supported upon appropriate legs. Side walls 2 are provided on their inner surfaces with longitudinally extending vertically spaced bars 4 and 5 providing between them channels in each of which are mounted slide bars 6 united at one end beyond the frame in a connecting plate 7 to which is pivotally connected a pitman 8. A belt or other power-driven wheel 9 is formed at different radial distances

from the center with openings 10, 11, 12 and 13. These openings are designed to provide for the connection of the pitman 8 to the power wheel 9 and obviously provide for different length throws or movements of the bars 6.

The bars 5 are provided near their upper ends with channels 28 to receive cross-bars 14 which are thus mounted to be adjusted longitudinally of the bars 5 so that the space between any pair of cross-bars 14 may be adjusted. In the instance shown, there are two sets or pairs of such cross-bars 14 and the space between these bars is to be regulated through positioning in selected channels 28 to receive the length of block 15 from which the shakes are to be split. The block is 15 positioned between the side bars 2 of the frame and between a pair of cross-bars 14, thus permitting the block to be merely placed in position, provided, however, that if desired holding blocks 27 may be mounted upon the blocks 15 and prevented from endwise movement though permitted adjustable vertical height, to accommodate the blocks originally and as they are split away, by pins projecting from the blocks 27 and guided between uprights 29, as clearly illustrated, as the 20 cross-bars 14 prevent endwise movement of the block during operation of the machine.

The block of material is loosely confined between the bars 14, at the same time the bars act as abutments for the block at the time the wedge 30 splits a shake. In order to facilitate the splitting action and enable the wedge to follow the grain of the wood and thereby properly shape the shake, the block of material tilts slightly.

Secured to the longitudinally operating bars 6 35 is a splitting element 16, which element is an appropriate length of metal having rather abrupt ends terminating at each side edge in a splitting edge 17 which is naturally sharpened. The thickness of the splitting element 16 increases 40 from the abrupt side edges or ends toward the center, being thicker at the center, as indicated at 18 in Figure 8.

Beyond the splitting element, the bars 6 are connected by a supporting plate 19. The supporting plate is secured to the under side of the bar but is presented with an upstanding offset 20 fitting a recess 21 in the inner surfaces of the bars 6, so that the supporting plate is on a horizontal plane below that of the splitting element 50 which is secured to the upper surfaces of the bars 6. The splitting wedge has its end seated in a transverse recess 22 in the upper surfaces of the bars 6, being secured by a bolt 23, the lower end of which is provided with a securing nut 24 seated 55

in an opening 25 in the lower surfaces of the bars 6. The connection described, and which is shown more particularly in Figures 4 and 5, permits vertical adjustment of the splitting element 5 as a whole in order to select a desired thickness of the butt end of the shake to be produced.

In the instance shown, the machine is designed for two blocks and the splitting element 16 and supporting plate 19 will be duplicated, as indicated in Figures 2 and 3.

In operation, the blocks 15, or one such block if only one is to be used, are placed in position between the appropriate pair of cross-bars 14. These cross-bars have been adjusted to prevent undue endwise movement of the block in the splitting operation and the block in position rests upon the particular underlying supporting plate 19. In the driving of the power wheel 9, the bars 6 are moved in one direction, the splitting element 20 is caused to enter the end of the block, but incident to its construction, compels a splitting operation rather than a cutting operation.

This splitting operation incident to the formation of the block follows the grain of the block 25 in a taper, so that the resultant shake is tapered from one end to the other. As the splitting element moves through the split and beyond the block at the opposite end, the corresponding movement of the supporting plate 19 permits the 30 split shake to drop free of the plate into a pile in the lower portion of the frame. The splitting element is now beyond the opposite end of the block and as the movement of the power wheel is continued, the bars 6 are moved in the opposite direction and a second shake is split from the block 35 with the butt end at the opposite end of the block. Thus, in a reciprocation of the pitman, two shakes are formed, as will be plain from Figures 2 and 3 of the drawing. Furthermore, if two blocks are 40 used and the splitting element and supporting element are duplicated, the apparatus will form two shakes at each movement of the supporting bars 6 or four shakes in each complete reciprocation of the bars.

If longer shakes are to be produced than the minimum for which the machine is adapted, the cross-bars 14 are adjusted to accommodate the greater length of block and the vertical position of the splitting element 16 is adjusted and 50 through the obvious use of supporting means in the channel 22 below the connected portion of the splitting element, so as to increase or decrease the thickness at the butt end of the shake for providing the different desired lengths of shake.

It is to be particularly noted that the splitting elements do not cut the material. In cutting through the material of the block, there is necessarily approximately the same thickness of material of the block divided by the cutting whereas 60 through the use of the improved splitting element, which splits and does not cut, it will be apparent that the wedge formation of the splitting element causes that portion of the block divided by the initial split to be forced to bend downwardly, thus splitting the shake from the block ahead of the splitting element, resulting in a breaking of the fiber and bringing the shake to the desired taper and presenting at the same time that desired roughness or grain-showing highly desirable in articles of this character.

What is claimed to be new is:

1. A shake making apparatus including a frame having side and end bars, upper and lower guide bars secured on the inner surface of each side

bar and spaced apart to provide a guideway, slide bars movable in the respective guideways, a splitting tool arranged transverse and connected to the respective slide bars, the ends of the tool fitting in notches in the respective slide bars, with the notches of a depth exceeding the maximum thickness of the tool to thereby accommodate and provide for vertical adjustment of the tool with respect to the slide bars without projecting the tool above the upper surface of the slide bars, a material block supporting plate connected to the respective slide bars, said plate having offset terminals secured to the lower surfaces of the slide bars, with the offset terminals of a depth to hold the supporting plate in a position below any possible position of the tool in the slide bars, means for reciprocating the slide bars to simultaneously operate the tool and supporting plate, the upper guide bars being formed with a series of notches extending longitudinally of said bars, and cross bars loosely fitting similar notches of the respective guide bars to hold the material block against longitudinal movement on the supporting plate during operation of the knife.

2. A construction as defined in claim 1, including holding blocks to rest upon the upper surface of the material block and means carried by the upper guide bars for preventing longitudinal movement of the holding block without interfering with free vertical movement thereof.

3. A shake making apparatus, comprising a frame, upper and lower guide bars secured on the inner surfaces of the frame and spaced apart to form guideways, slide bars movable in the respective guideways, a wedge arranged transverse and connected to the respective slide bars, a material block supporting plate connected to the respective slide bars, the upper surface of the plate being below the path of movement of the wedge and spaced therefrom, means for loosely confining a material block on the plate to permit a slight movement of the block in the direction of movement of the wedge and tilting of the block in the formation of a shake, whereby when the wedge is advanced toward the block of material on the plate, the wedge will split a shake from the block, the forward end of the shake passing between the plate and wedge and the block falling in position for formation of a subsequent shake.

4. A shake making apparatus, comprising a frame, upper and lower guide bars secured on the inner surfaces of the frame and spaced apart to form guideways, slide bars movable in the respective guideways, a two-edge wedge arranged transverse and connected to the respective slide bars, a material block supporting plate connected to the respective slide bars, the upper surface of the plate being below the path of movement of the two-edge wedge and spaced therefrom, means for loosely confining a material block on the plate to permit a slight movement of the block in the direction of movement of the wedge and slight tilting of the block in the formation of a shake, means for reciprocating the two-edge wedge whereby when the two-edge wedge is advanced in one direction toward the block of material on the plate, the wedge will split a shake from the block, the forward end of the shake passing between the plate and wedge and the block falling in position to be acted on in the reverse movement of the wedge in the formation of a subsequent shake.
